INFANT RESPIRATOR

Birchard M. Brush, Westminster, Colo., assignor to J. J. Monaghan Company, Inc., Denver, Colo., a corporation of Colorado

Filed Apr. 8, 1959, Ser. No. 55,407

Term of patent 14 years

(Cl. D83—1)

FIG. 1.

FIG. 2.

FIG. 3.

FIG. 4.

FIG. 5.

Figure 1 is a front elevation of an infant respirator showing my new design;

Figure 2 is a left side elevation;

Figure 3 is a horizontal cross-sectional view taken along line 3-3 of Figure 1 looking downward onto the top of the cabinet;

Figure 4 is a horizontal cross-sectional view taken along line 4-4 of Figure 1 looking downward into the lower half of the body shell; and

Figure 5 is a fragmentary right end elevation of the body shell.

The rear and the right side of the cabinet housing are substantially plain.

I claim:

The ornamental design for an infant respirator, as shown and described.
